FREEWHEELING RESILIENT CORD DRIVE

Fred A. Fasano, Richmond Hill, N. Y.

Application August 22, 1951, Serial No. 243,005

8 Claims. (Cl. 46—206)

1

This invention relates to toy vehicles and has for its main object to provide novel improved driving means for the same.

Particularly it relates to toy vehicles which are propelled by a resilient cord or band which is wound on a shaft, stressed, and then, when released, will rotate the shaft. An object of this invention is to prevent a reverse winding of the resilient cord on the shaft which would cause a brake action on the vehicle, but, just the opposite, to permit a free rotation of the shaft in said reverse direction.

My invention also has for an object to provide novel means for the securing of the resilient cord on the shaft, to permit said free rotation, or a so-called "free wheeling" thereof after the resilient cord is unwound from the shaft by a self-releasing of the cord from the shaft.

Still another object of my invention is to provide a novel securing means for the cord on the body of the vehicle whereby an automatic self release of the other end of the cord, usually permanently secured on the body of the vehicle, is also provided for and so an excessive stressing and possible breaking of the cord is avoided.

Still further objects of my invention will be apparent as the specification of the same proceeds, or will be pointed out therein, and, among others, I may mention: to provide a resilient cord drive of the many advantages indicated hereinbefore, which still will be simple in construction, inexpensive to manufacture, and adapted to be easily applied to toy vehicles now on the market.

In the drawings forming a part of this specification and accompanying the same:

Fig. 1 is a diagrammatic sectional view of a toy vehicle to which the preferred embodiment of my free wheeling drive has been applied, and

Fig. 2 is a diagrammatic bottom view thereof;

Fig. 3 is a fragmentary plan view of the driving shaft for said preferred embodiment of my novel free wheeling resilient cord drive, and

Fig. 4 is a sectional fragmentary perspective view thereof, while,

Fig. 5 shows a loop end of the resilient drive cord used on said shaft;

Fig. 6 is a fragmentary plan view of a modification of my invention;

Fig. 7 is a fragmentary bottom view of a rear portion of a toy vehicle showing my novel self releasing securing of the resilient driving cord on its body;

Fig. 8 is a sectional view thereof, the section being taken on the line 8—8 of Fig. 7;

Fig. 9 shows another modification of my inven-

2

tion wherein the free wheeling and the self releasing features of the device are combined in one construction.

Fig. 10 shows a wire guide in detail.

Referring now to the drawings more in detail, by characters of reference, the numeral 20 indicates a toy vehicle, in general, to which the preferred embodiment of my invention has been applied, and it has a downwardly open body 21, the two shafts 22 and 23 with a pair of wheels 24 secured on each, said shafts being journaled in the vehicle 20 by any appropriate means.

An elastic cord 25 is used for self propelling action and it may have a loop 26 at one end 15 thereof engaging the front shaft 22 in a groove 27 in a manner to be explained hereinafter, while the other end 28 of the resilient drive cord is secured at the rear portion of the vehicle 21, preferably in a manner to be inclined to the shaft 22 forming an acute angle therewith, as indicated at 29.

In Figs. 3 and 4 the engagement of a loop 26 at the end of the elastic drive cord or band 25 with the shaft 22 is indicated more in detail and 25 on a larger scale.

It will be seen that a circular groove 27 is formed in the shaft and the resilient cord or band 25 is terminated in a non-elastic cord or thread loop 26 which is arranged in the groove 27.

Said groove also is provided with an inclined short branch 30.

The operation of my device is as follows:

The device is placed in the position indicated in Fig. 1 on an appropriate support like the ground or floor 31, and then will be moved rearwardly, as indicated by the arrow 32, being pressed against the floor 31 to a desired extent, as indicated by the arrow 33. This will cause the shaft 22 to rotate in the direction of arrow 34, as indicated in Fig. 4. Due to the inclined position of the cord or band 25 and the direction of the branch 30 of the groove 27, the loop end 26 of the cord 25 will be caught by said branch and the rotation of the shaft will cause the cord 25 so fixed to be wound around the shaft 22, as indicated by the dotted lines 35 in Fig. 3, and said winding up will cause stress in the cord 25.

When the moving of the vehicle in a rearwardly direction under the pressure 33 is stopped and the vehicle released the tension of the stretched elastic cord 25 will cause the shaft 22 to turn in a reverse direction, as indicated by arrow 36, Fig. 4, and will cause the vehicle to quickly run in a forward direction, arrow 37.

Driving a toy vehicle by a resilient cord wound

on the shaft in one direction and permitted to unwind in the reverse direction, has been proposed heretofore. However, after an entire unwinding of the turns of the resilient cord from the respective shaft in the vehicle, with such drives heretofore proposed, in most cases the elastic cord 25 will start to be wound on the respective shaft in the opposite direction, thereby effecting a braking action on the vehicle and causing it to stop after a comparatively short run, and its run will also be executed with a reduced speed.

Various methods have been proposed to prevent such a braking action of the driving resilient cord to make the vehicle of a so-called "free wheeling" type, but the devices heretofore proposed for this purpose have been either inefficient, or very complicated and expensive, or both. The described simple groove 27 with its branch 30 in my invention will make the shaft 22 self wheeling with the least possible construction and cost of manufacturing and in a very efficient reliable manner.

By observing the drawings, it will be seen that when the shaft 22 rotates in the direction of arrow 36, that is, in the opposite direction in which the resilient cord was wound up on the same, then the shaft will rotate freely in the loop 26 at the end of said cord without winding the cord on the shaft in the opposite direction and without causing said braking action. When the shaft rotates in the direction of arrow 36, the branch 30 will not catch the loop 26 and the same may revolve loosely around the shaft without being wound on it.

Through my invention the vehicle 20 after being wound up for self propelling action by being moved under pressure rearwardly, will shoot forwardly and will run in that direction much longer than was the case with the former devices of similar type and also with a stronger force and greater speed thereby making the toy more interesting to children. The toy obviously also will have a novel educational effect.

It is to be understood that the loop 26 will be formed of usual non-resilient cord or thread and I prefer to form the loop 26 for the cord 25 in the manner indicated in Fig. 5 whereby a portion 26a of it will be turned over the shaft, as indicated in said figure, then will be turned back as at 26b to form a doubled loop proper portion 26c and will be secured on the portion 26a, as shown at 26d. In a word, a so-called "slip knot" is formed from the non-resilient cord or thread portion 26a. The slip knot so formed will have the tendency of tightening on the shaft 22 when it rotates in the winding up direction, arrow 34, while it will automatically loosen and will permit a free rotation on the shaft 22 when it is rotated in the opposite direction, arrow 26. This loose reverse rotation however would not be certain and efficient in case loop 26 were made by a resilient cord. At 26c the securing of 26a to the resilient cord 25 is indicated.

In Fig. 6 a modification of my self winding free wheeling drive for toy vehicles is illustrated. In this modification instead of the groove 27 with a branch 30, a piece of wire 40 is wound in a screw like manner over the shaft 22 having a helically wound main portion 41 forming a part of a screw thread curve and ending with similarly curved inclined short termination portions 42 and 43. The loop 26 is arranged adjacent to the frictional screw shaped wire device 40 and the resilient drive cord 25 will have an inclination from the loop 26 towards said wire device 40. When

the vehicle 20 is pushed rearwardly under pressure, shaft 22 will rotate in a clockwise direction, as indicated by arrow 44, and in such a movement the end 26a of the cord 25 adjacent to the loop 26 will be caught between the terminations 42 and 43 of the screw thread shaped wire 40 and thereafter the cord 25 will be wound on the shaft 22 to the right of the device 40, as indicated at 45 by dotted lines, similarly as was the case with the preferred modification of my device and indicated at 35 in Fig. 3. In this manner the resilient cord 25 will be stretched and when the vehicle is released, it will drive the vehicle in a forward direction, and after the windings 45 are entirely unwound, the shaft 22 will keep rotating in the opposite direction, arrow 46, and it will be seen that in this direction the screw thread shaped wire will have no tendency to catch the loop 26 or the respective end of the cord 25. Loop 26 will be loosened and will slide alongside the device 40 without being caught by it and the shaft will be free wheeling.

In Figs. 7 and 8 I show a self releasing securing of the cord 25 on the rear 41 of the body of a toy vehicle 20. For this purpose I preferably secure a spring arm 48 on the rear of the vehicle, as indicated at 49, said arm having an angularly bent curved termination 50. The cord 25 will have a loop 51 at its end whereby it is hooked on the termination 50 of the arm 48.

Normally the arm and the cord are in the position indicated by the full lines in Figs. 7 and 8. However, after a certain amount of winding, the cord 25 will move in a left hand direction, arrow 52, and after such winding it will take the left hand inclined position 25a and in such position obviously it will slide off the termination 50 of the arm 48 whereby, after a predetermined winding, the cord 25 will not be further wound on the shaft 22. It will slide off but will be ready to be returned on the arm 48 for a new winding action on the shaft of the vehicle.

It will be seen that the limit of winding of the cord 25 on the shaft 22 and the stretching of said cord may be arranged in such a manner as to automatically prevent a breaking of the cord, it being self releasing before the danger point.

If the arm 48 is made of spring material it also will be bent to the left as indicated at 48a thereby facilitating the release of the cord 25.

Such a resilient arm also will snap back after such release and may make a noise upon striking the vehicle body and thereby indicate that the cord end was released and must be returned manually.

In Fig. 9, finally, I show a second modification of my device for driving the shaft 22 by an elastic cord 25 in which modification both, the free wheeling and self releasing are obtained with one simple means. In this modification a wire 60 is turned around the shaft 22 in a very tight manner so as to prevent a rotation thereof on the shaft. The wire will have a curved termination or finger 61 projecting from said shaft and a loop 62a of the cord 25 will be hooked onto said finger 61. It will be seen that when the shaft 22 is rotated in the direction of arrow 62, cord 25 will be wound around the shaft, will be stretched, thereby preparing for a driving of the vehicle. When such a winding is stopped and the vehicle freed, the cord 25 will start to wind the shaft in the opposite direction, and when all its former windings on the shaft 22 has been unwound, it will automatically slip off the finger 61 and permit a free wheeling of the shaft 22.

In this modification obviously the cord 25 has to be hooked over the finger 61 at every renewed operation of the device. To make such a renewed hooking of the cord on said finger easy and automatic, I may provide a guide device 63 projecting from the side of the vehicle and having parallel wires between which the cord 25 may slide. A knot or other limit member 64 may also be provided in the cord 25 so that upon a freeing of the cord from the finger 61 it will be retained by the guide 63 in a position ready for an easy hooking of the same on the finger 61.

In the form of the guide shown in Figs. 9 and 10, a wire 66 will have a front wider doubled portion 67, and a rear closer doubled portion 68. A loop 62a at the end of resilient cord 25 will be held in a flat horizontal position between the wires 67. The elastic cord 25 then passes between wires 68 which are closer set and will not permit the passage of knot 64 and the loop 62a. On rotation, as indicated by arrow 62 finger 61 will automatically catch loop 69, but on the reverse rotation it will just rub against it without hooking into it.

I may remark that a very simple one direction drive according to my invention may be provided by using the slip knot 26 earlier described, on a shaft without any special construction on the shaft. In this case, however, the knot may have to be of elastic cord and may not permit an easy loose rotation therein of the shaft in a reverse direction.

Also, certain portions of my device in the drawings have been shown in an exaggerated manner for the sake of clearness, so for instance, in Fig. 6, knot 26 is set at an exaggerated distance from the wire 40, while in reality it will be very close to it.

Instead of the single slip knot shown in the drawings particularly in Fig. 5, double thread slip knots may be used particularly when the shaft 22 is very small.

I also may remark that instead of the wire screw thread portion shown in Fig. 6, a wire coil spring may be used which may be pushed over the shaft retaining its position by frictional engagement and the front end of which is used to catch the cord in one direction while permitting it to pass in the other direction. This construction is materially cheaper to manufacture and easier to apply.

I also may use an appropriate clamp on the shaft instead of a loop and hook the end of the resilient cord on a finger on the clamp, causing to wind up on the shaft in one direction, but slipping off the clamp in the other direction of rotation.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention in some detail what I claim as new and desire to protect by Letters Patent of the United States, is:

1. In a toy vehicle, a body, a shaft journalled on the body, wheels fixed on the shaft for rotation therewith, a cord having an elastic portion connected at one end to the body, a loop at

the other end of the cord, said cord passing through said loop, and said loop and the portion of the cord adjacent thereto surrounding said shaft, and means on the shaft and adjacent said loop to engage said loop upon rotating said wheels and shaft in one direction whereby to wind said cord about said shaft for stretching the elastic portion of said cord and whereby upon release of said wheels and shaft the stretched elastic portion of the cord will rotate said shaft and wheels in an opposite direction and unwind from said shaft, said loop engaging means being arranged to release from said loop when the cord is fully unwound whereby to permit said shaft to continue rotating freely in said opposite direction without winding said cord.

2. The combination of claim 1, said loop engaging means comprising an annular groove formed in the shaft receiving the portion of the cord adjacent said loop, and further comprising a groove in the shaft offset from the annular groove helically.

3. The combination of claim 1, said shaft extending transversely of the body and said cord extending in a direction inclined to the shaft.

4. The combination of claim 1, the connection between the cord and the body comprising means fixed on the body and releasably engaging said cord and adapted to release the cord when the cord is stretched to a predetermined tension.

5. The combination of claim 1, said loop being made of non-elastic material.

6. In a toy vehicle, a body, a shaft journalled on the body, wheels fixed on the shaft for rotation therewith, a cord having an elastic portion connected at one end to the body, a loop at the other end of the cord, said cord passing through said loop, and said loop and the portion of the cord adjacent thereto surrounding said shaft, and means on the shaft and adjacent said loop to engage said loop upon rotating said wheels and shaft in one direction whereby to wind said cord about said shaft for stretching the elastic portion of said cord and whereby upon release of said wheels and shaft the stretched elastic portion of the cord will rotate said shaft and wheels in an opposite direction and unwind from said shaft, said loop engaging means being arranged to release from said loop when the cord is fully unwound whereby to permit said shaft to continue rotating freely in said opposite direction without winding said cord, said loop engaging means comprising an annular groove formed in the shaft receiving the portion of the cord adjacent said loop, and further comprising a groove in the shaft offset from the annular groove helically, said loop engaging means comprising a helical ridge on said shaft and adjacent said loop and said cord being inclined from the shaft toward said ridge.

7. In a toy vehicle, a body, a shaft rotatable on the body, wheels on the shaft, a cord, a loop at one end of the cord, said cord passing through the loop, and the loop and the portion of the cord adjacent thereto surrounding the shaft, means on the shaft to engage the loop upon rotating the shaft in one direction to wind the cord about the shaft, means interconnecting the cord with the body and adapted to be tensioned when the cord is wound on the shaft whereby to exert pull on the cord to unwind the cord and rotate the shaft in an opposite direction, said loop engaging means being arranged to release from the loop when the cord is fully unwound whereby to permit the shaft to continue rotating in

an opposite direction freely without winding said cord after the cord is fully unwound.

8. In a toy vehicle, a body, a shaft rotatably mounted thereon, wheels on the shaft, an elastic cord, means to attach one end of the cord to the body, a non-elastic cord having one end attached to the elastic cord, a loop at the other end of the non-elastic cord, said non-elastic cord passing through said loop, and said loop and the portion of the non-elastic cord extending therefrom surrounding said shaft, means on the shaft to engage said loop upon rotating said shaft in one direction to cause the non-elastic cord and the elastic cord to wind on the shaft whereby to tension the elastic cord whereby to cause the portion of the cords wound on the shaft to unwind, and whereby to rotate the shaft in an opposite direction, said loop engaging means being arranged to disengage from the loop when the

15 cords are fully unwound, whereby to permit the shaft to continue rotating in an opposite direction freely without rewinding the cord.
